J. H. LAIRD

HEADLAMP

Filed March 13, 1924

INVENTOR:

John H. Laird

BY

Albert Allen

ATTORNEYS.

UNITED STATES PATENT OFFICE.

JOHN H. LAIRD, OF LOUISVILLE, KENTUCKY.

HEAD LAMP.

Application filed March 13, 1924. Serial No. 699,053.

My invention relates to headlamps for vehicles and the like, in which the object is to project the light without glare to approaching or passing persons, and still to illuminate with the highest efficiency those portions of the roadway which require it for safe driving.

It is my object in the first place to provide a reflector based on other than a single parabola of revolution, and in defining the concavity of the reflector, it is my object to provide for a definite series of curves, easy to plot for various sizes of lamps, and having definite action in the deflection of light rays. Many of the reflectors of the patent art require a combination of more than one reflector, and while a single cross section of such a combination may be effective, it is exceedingly difficult in manufacturing, making dies, etc., to provide for the plurality of meeting edges, and as a result the light rays are not reflected so as to give a maximum intensity from the source of light.

My reflector curves are designed to accomplish the following features: (a) A bright line of light in a horizontal plane or dipping slightly from the height of the reflector which will brilliantly light the road directly ahead of the vehicles. (b) A diffused light illuminating the roadway at the sides without any rays which pass upwardly from the horizontal, so as to create a glare. (c) Bright light adjacent the vehicle and immediately to the sides thereof for safety against accident and so that when the headlamps are dimmed, there will be enough light to drive. It should be noted, however, that it is entirely unnecessary to dim the lights in my headlamps, except perhaps when the plane of the vehicle frame, as in passing over the brow of a hill, is such as to project in improper angle to the road, although it will always maintain its angle to the vehicle.

I provide in addition for the use of a deflector element in the reflector which cuts out direct rays from the bulb, and deflects them back onto the main reflector in such a way as to waste no candle power, but to avoid direct view of the bright spot in the lamp bulb from the front of the lamp.

I accomplish my objects by that certain construction and arrangement of parts to be hereinafter more specifically pointed out and 55 claimed.

In the drawings:

Figure 1 is a diagrammatic section of a reflector taken on a vertical plane through its center.

Figure 2 is a front elevation of the reflector also partially diagrammatic.

Figure 3 is a perspective view of the reflector complete with deflecting element in place.

Figure 4 is a section taken on a central vertical plane through Figure 3.

It is known that a catenary curve, possesses certain functions dependent upon the depth thereof as compared to the distance 70 between its ends. A catenary is a curve which will be formed by a flexible element of uniform character throughout, suspended from its ends. Such a curve has known functions which can be plotted by mathematical formula, and can be used practically in forming dies, by means of which to form up a reflector.

A catenary curve is close to a parabola at its central portion or apex, and dependent 80 upon the spacing of its ends with relation to its depth, i. e., its horizontal component, can be formed so as to tend toward an ellipse at its ends.

Thus I form the upper portion of my reflector by one half of a catenary curve 1, revolved on the axis of the curve through a half circle. This portion of the reflector will then provide for general illumination of the roadway by light rays projecting at 90 all angles except upwardly from the horizontal.

In the diagram of Figure 1, the curve 1 is shown, and the nature of the curve is designed to provide the desired light pattern. By spreading the ends of the curve, the light rays can be given less and less convergence, until the ends pass beyond the limits of a parabolic curve having coincidence at the apex and having a focal distance equal to the parameter of the catenary. Thus the catenary of my reflector must have a horizontal component which is less than the component of a parabola having a focal

distance equal to the parameter of the catenary, so that light rays coming from the focus of the catenary to points away from the apex of the curve will be reflected convergingly toward the axis of the curve.

Another way of defining a catenary in terms having direct application to the problem of light reflection, is that a catenary is a curve in which the angle of reflection varies regularly and increasingly with relation to the axis of the curve as the angle of incidence is decreased in lines drawn from the focus of the curve considering it as a parabola but never reaches an angle at right angles to the said axis.

A desired portion of the lower half of the reflector is formed as a parabola of revolution, said parabola having the same focus, as the catenary. In the diagram of Figure 2, I have shown part of the lower portion of the reflector as formed of such a parabola of revolution. The parabola is defined between lines 2-2, and is shown in Figure 1 in section at 3.

The remainder of the reflector, viz: the walls extending down from the central horizontal plane will be curved as regularly as possible so as to smoothly join with the two curved areas already noted. This portion of the reflector is indicated in Figure 2 as lying in the areas 4 and 5.

Now imagine a source of light located at the point 6 which is assumed to be the focus of the catenary and of the parabola. The rays striking the parabola will be reflected in a straight line parallel to the axis of the parabola, which will form the narrow line of light providing features (a) above noted. The rays of light striking the parabola are indicated by dotted lines 7.

The rays of light striking the catenary will be reflected almost parallel with the axis thereof, at the apex of the reflector, and as they depart from the center will be gradually converged crossing the axis of the curve, at all times and gradually approaching in their point of crossing of the axis, toward the focus of the curve.

Since all of the rays must cross the axis, which is a function of a catenary, it is evident that no rays can escape upwardly, and shine in the eyes of passers-by since all rays will be reflected from a point above the plane of the axis, or exactly on the plane thereof.

The rays of light from the portions 4 and 5 of the reflector will be thrown at a slant across the reflector and down, thereby brightly lighting the sides of the road close to the lamps.

The area of the portions 4 and 5, and the amount of the lower portion of the reflector which will be defined by a parabola of revolution, will be determined from

the light pattern required of the lamp. The horizontal component of the catenary portion of the reflector will be determined by the required light pattern also, dependent upon the amount of light needed near the lamp, and the amount needed at the sides of the central beam at a distance from the lamp.

Referring to Figures 3 and 4, it will be noted that the reflector has a circular flange 8, having the usual channel 9 for a felt strip, and that the space which is required to fill out the circle from the catenary is formed as part of the reflector, as at 10.

The catenary portion of the reflector is indicated at 11, the parabolic portion at 12, and the two filling in curves at 4 and 5, as in the diagram.

Located in the reflector at the apex is a device formed of a metal ring 13, in a single plane, and set in the horizontal plane of the lamp. This ring has a spherical section 14, which is designed so as to act as an opaque body cutting off rays of light which would emanate from the bulb and miss striking the reflector at the front thereof, and above the said horizontal plane. It also has a spherical section 15, which is designed to screen that portion of the apex of the reflector that would reflect rays toward the spherical reflector in such a way as to ultimately result in light striking the parabolic portion thereof from other than its focus. Both of these sections are formed with a focus coincident with the focus of the parabolic portion of the reflector and at this focus the filament of the light bulb should be placed. There is a space between the two spherical sections sufficient to permit all light rays which can safely be permitted to strike the upper portion of the reflector to impinge upon it directly. The concave faces of the sections are painted white or silvered to act as reflectors, so that all light rays from the lamp are eventually emitted from the front of the lamp body.

This device is described more fully in my pending application for patent Serial No. 662,111 filed September 11, 1923, to which reference is hereby made.

I include this device in the present embodiment, in order to make it as perfect as possible, and it is evident that with the reflector built as I have now described it, and with the deflector unit installed, the light rays all are conserved and none escape in other than a direction which can be mathematically predetermined.

Having thus described my invention, what I claim as new and desire to secure by Letters Patent, is:—

A lamp having a reflector formed with the part thereof above the horizontal plane

thereof as a catenary of revolution adapted to the parameter of the catenary, and with to reflect rays of light striking the same from a focus convergingly toward the horizontal axis of the reflector, and with a portion located centrally of the lower half of the reflector formed as a parabola of revolution having its focus at a distance equal to the parameter of the catenary, and with the intermediate portions from the horizontal plane to the beginning of the parabola curved off to smoothly join the two curves of revolution already noted. 10

JOHN H. LAIRD.
